UNITED STATES PATENT OFFICE.

JOSEPH H. TEMPLIN, OF PHILADELPHIA, PENNSYLVANIA, ASSIGNOR, BY MESNE ASSIGNMENTS, TO SANTO MANUFACTURING COMPANY, OF PHILADELPHIA, PENNSYLVANIA, A CORPORATION OF DELAWARE.

DOUBLE-ACTING DIAPHRAGM-PUMP.

1,171,561.

Specification of Letters Patent.

Patented Feb. 15, 1916.

Application filed March 17, 1909. Serial No. 484,046.

To all whom it may concern:

Be it known that I, JOSEPH H. TEMPLIN, citizen of the United States, residing at Philadelphia, in the county of Philadelphia and State of Pennsylvania, have invented certain new and useful Improvements in Double-Acting Diaphragm-Pumps, of which the following is a specification.

My invention relates in general to a novel construction of a double acting diaphragm pump, preferably air pumps, and its essential object is to reduce the friction of the moving parts thereby utilizing the full motive force to produce the resultant vacuum or air pressure.

Another object is by means of a simplified construction to reduce the noise, also the weight and cheapen the cost of construction. And furthermore to prevent loss of power by leakage which occurs around the pistons of double acting diaphragm pumps as usually constructed.

It consists also of other novel features as hereinafter more fully described.

In the accompanying drawings, Figure 1 is a view, partly in side elevation and partly in vertical section, of the pumping mechanism embodying my improvements; Fig. 2 is a sectional view on the line B—B of Fig. 1; and Fig. 3 is a detail view in end elevation, showing the connection of the yoke to the operating crank.

Similar letters refer to like parts throughout the several views.

A represents a yoke provided with a pair of platens B' and B'' to each of which are secured the diaphragms C and D, respectively; the diaphragms are in turn, by means of clamping rings E and E' and also bolts F, secured to the air chambers or casings G and G'; these casings are conveniently constructed so that suitable inlet valves H and H' and suitable outlet valves I and I' are readily accessible and allow the free ingress and egress of the air as desired. The yoke A is connected by links L—L to crank arms M—M carried by the rotating shaft N of the actuating motor. The links L—L, as clearly shown in Fig. 3 of the drawing, are formed of two members which are rigidly connected to the yoke A, and are also rigidly connected to bearing blocks which coöperate respectively with the cranks M—M.

In the illustrations it can be readily un-

derstood that no guides or cross heads are required, for as the yoke is reciprocated the diaphragms slacken in the center of the stroke thereby permitting the rocking of the direct connections.

The operation of the device is as follows:—Applying motive force by means of cranks or levers and reciprocating the yoke causes the diaphragms attached to the yokes to pass in and out of their respective casings displacing and discharging the air through their respective inlet and outlet valves and also their inlet and outlet ports alternately.

It will be readily seen that this double acting system requires fewer moving parts and no possibility of leakage as compared with the double acting system wherein a single diaphragm is used and operated by a piston requiring guides, stuffing boxes, and connecting rods nicely machined, and furthermore the advantages of this double acting diaphragm over the single acting diaphragm are, that when the pump is used for exhausting air, the vacuum on one diaphragm at the extreme end of its outward stroke tends to return the diaphragm and through the yoke returns the opposite diaphragm to central position thereby assisting the cranks and balance wheels to store up energy to pass the opposite center and vice versa, which action is effected to a greater degree of economy of power in this construction as the yoke is free to move without any frictional contact whatever and therefore requires the least possible operative power.

It is to be understood that while I prefer the illustrated construction of parts as I find them the most economical I do not wish to confine myself to them especially, as it is apparent that the precise construction of the valves, chambers or casings and various parts can be varied and still further changes be made, by those skilled in the art, which may come within the scope of my principle and invention.

What I claim as my invention is:—

1. A double acting pump including in combination a pump casing open at each side, a transverse partition dividing the pump casing centrally thereof, said partition having a chamber formed therein with openings leading from each side of the partition, valves for said openings, a flexible

2

diaphragm attached to each outer end of the pump casing, each diaphragm being of slightly greater area than the area of the respective ends to which it is attached, a circular platen attached to each diaphragm centrally thereof, said platen being of less diameter than the inner end of the casing whereby each diaphragm and platen may be vibrated across a plane containing the connection of the diaphragm to the casing, a rigid yoke connecting said platen, a rotating shaft, eccentric members carried by said rotating shaft, links connected to said yoke at opposite ends thereof and coöperating directly with the respective eccentric members.

2. A double acting pump including in combination, a pump casing open at each side, a transverse partition dividing the pump casing centrally thereof, said partition having a chamber formed therein with openings leading from each side of the partition, valves for said openings, a flexible diaphragm attached to each outer end of the pump casing, each diaphragm being of slightly greater

area than the area of the respective ends to 25 which it is attached, a circular platen attached to each diaphragm centrally thereof, said platen being of less diameter than the inner end of the casing whereby each diaphragm and platen may be vibrated across a 30 plane containing the connection of the diaphragm to the casing, a rigid yoke connecting said platen, a rotating shaft, eccentric members carried by said rotating shaft, links connected to said yoke at 35 opposite ends thereof and coöperating directly with the respective eccentric members, each of said links having a rigid connection with the yoke and a rigid connection with the bearing block coöperating with the eccentric members.

In testimony whereof I affix my signature in presence of two witnesses.

JOSEPH H. TEMPLIN.
